UNITED STATES PATENT OFFICE.

FRANCIS W. TULLY, OF BROOKLINE, MASSACHUSETTS.

GLOVE-STRETCHER.

1,199,721.

Specification of Letters Patent. Patented Sept. 26, 1916.

Application filed November 10, 1915. Serial No. 60,790.

To all whom it may concern:

Be it known that I, FRANCIS W. TULLY, a citizen of the United States, and resident of Brookline, in the county of Norfolk and 5 State of Massachusetts, have invented new and useful Improvements in Glove-Stretchers, of which the following is a specification.

This invention relates to glove stretchers, and its object is to provide a stretcher particularly adapted for ready insertion into a 10 wet glove to hold the glove in shape while drying, or into a crumpled glove to restore its proper shape and retain it until the glove is again worn.

15 A further object is to provide a stretcher for these and similar purposes which may be so economically made as to warrant its sale at a very low price, or even to permit it to be given away for advertising purposes or the 20 like.

Referring to the drawings which illustrate an embodiment of my invention,— Figure 1 is a plan view of my improved stretcher; Fig. 2 is a section on the line 2—2, 25 Fig. 1; Fig. 3 is a view similar to Fig. 2, but showing the stretcher in partly contracted position; and Fig. 4 is a section on the line 4—4, Fig. 1.

My improved stretcher has the shape or 30 contour of a human hand, and is made of waterproof cardboard or any other comparatively stiff material, waterproof, or adapted to be waterproofed, and comparatively inexpensive. It consists of two 35 wings or sections A located side by side and hinged at B in any suitable manner, as by scoring. Each section or wing is cut or slashed to form an integral tab or tongue C, around which is passed a spring member, 40 such as an elastic band D, to hold said wings or sections in normal extended position shown in Figs. 1 and 2. Preferably the finger portions are concaved or dished, as clearly shown in Fig. 4.

45 When it is desired to insert the stretcher into a wet or crumpled glove, the user grasps the device at its wrist portion W and folds or swings the wings or sections A toward each other into the partly contracted position shown in Fig. 3. The stretcher is then 50 inserted into the glove, and when in the desired position the wings are released, whereupon the spring member D returns them to

normal extended position so that the glove is tightly stretched and retained. To remove the glove, it is necessary merely to swing or fold the wings toward each other in the manner already described, whereupon the glove can be readily drawn off.

It will be clear that my improved stretcher 60 above described provides an efficient means for restoring wet or crumpled gloves to proper shape, and retaining such shape until the gloves are dry or are again to be worn. It will be equally clear that the device may 65 be very economically made and therefore sold at a very low price, and that this fact coupled with the further fact that considerable advertising matter may be displayed thereon, makes the device well adapted for 70 advertising and so is of utility not only to the users of gloves but also to the sellers thereof.

I claim:

1. A glove stretcher comprising two 75 hinged sections located side by side, and means to hold said sections in extended position.

2. A glove stretcher comprising two hinged sections, and a spring member to 80 hold said sections in extended position.

3. A waterproof glove stretcher having the contour of a human hand, comprising two hinged sections located side by side and means to hold said sections in extended position.

4. A waterproof, cardboard, glove stretcher having the contour of a human hand, comprising two hinged sections located side by side and means to hold said sections in ex- 90 tended position.

5. A waterproof, cardboard glove stretcher having the contour of a human hand, comprising two hinged sections each provided with a tab, and a spring member engaging 95 said tabs to hold said sections in extended position.

6. A waterproof, cardboard, glove stretcher having the contour of a human hand with dished finger portions, comprising two 100 hinged sections each provided with a tab, and a spring member engaging said tabs to hold said sections in extended position.

Signed by me at Boston, Massachusetts, this 8th day of November, 1915.

FRANCIS W. TULLY.
